E. S. KELLEY

PAGE GALLEY AND TYPE TIE-UP

Filed May 11, 1927

UNITED STATES PATENT OFFICE.

EDWARD SYLVESTER KELLEY, OF NEW YORK, N. Y.

PAGE GALLEY AND TYPE TIE-UP.

Application filed May 11, 1927. Serial No. 190,425.

This invention relates to the art of printing and has particular reference to type galleries and tie-ups for type.

Whereas in the usual or old practice, it is customary to make up pages of type on a large make-up galley, and then to transfer the type to a smaller galley or page galley, in the practice of this improvement I employ only the smaller galley or page galley and omit the trouble and expense of the larger galley and the transfer of the type from one to the other.

Among the objects of the invention, therefore, is to provide a printer's galley upon which the column or columns of type are placed and locked by a special locking spring as distinguished from the use of a cord or other means for tying the work.

Another object of the invention is to provide a galley and tie-up mechanism so designed that the type will not only be satisfactorily locked on the galley, but is adaptable for correction or interchange of the type as may be necessary from time to time without disturbing the bulk of the type.

A still further object of the invention is to simplify the locking or tying means, making it easy for the locking to be effected for holding the type or to be released for removing the type from the galley.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is an end view of the structure of Fig. 2, looking from the plane of the line 1—1.

Fig. 2 is a plan view showing my improvement with the type locked to the galley.

Fig. 3 is an elevation of the lower end of the structure of Fig. 2, as from the plane of the line 3—3.

Fig. 4 is a transverse section on the line 4—4 of Fig. 2.

Fig. 5 is a perspective view of the locking spring.

Figs. 6 and 7 are detail views of the upper and lower end portions of the spring.

Referring now more specifically to the drawings I show my improved galley 10 as comprising a body and a series of vertical sides and ends 11, 12, and 13 extending upward from the plane of the bottom as usual and having one open side. This galley may be of any suitable construction, size, or design, but may be thought of in this description as a page galley and upon which a plurality of columns of type A and B may be placed with a reglet or spacer 14 between them. One end of the mass of type as usual abuts against the lower end wall 13, and the upper end of the type body is backed up by means of a transverse reglet 15. Obviously the reglets 14 and 15 are selected according to the width and length thereof according to the work under consideration.

The upper wall 12 of the galley is provided with a series of holes, slots, or openings 17 not far remote from the angle between this wall and the side wall 11. The lower wall 13 is provided with a somewhat similar series of openings 18 arranged adjacent to the end of the wall next to the open side of the galley. These openings 17 and 18 preferably are accurate as to spacing in accordance with the standard widths of columns and spacing between the columns. While I have shown three of these slots in each series, a greater or less number might be used and at variable spacing between them.

One of the principal features of my improvement is a spring shown in detail in Fig. 5 and made preferably of leaf spring material such as steel or its equivalent and comprising a substantially straight side leg 19 and a bow-shaped or curved leg 20 having a spring angle at 21 between them. While the leg 19 is described as being substantially straight, it is in normal idle position slightly angular as shown at 22 for the better gripping of the type when in locked position. Likewise while the portion 20 is described as bow-shaped, it has a substantially flat central portion 23 adapted to abut against the upper surface of the reglet 15. The end portions of the spring are both tapered and terminate in prongs or hooks, the leg 19 having a substantially right angularly turned hook 24 adjacent to which is a shoulder 25. The other end portion has a prong 26 adjacent to a shoulder 27.

After the type has been put into position on the galley and is ready for locking, the

operator grasps the spring 19 and projects the hook 24 through any convenient selected hole or opening 18, the spring at this time being swung outward as indicated in dot and dash lines in Fig. 2 so that the hook 5 will pass freely downward or outward through the slot after which the spring is swung to the left around into direct abutting engagement against the type column at the 10 right, the bowed portion 20 of the spring being brought at such time into the space between the reglet 15 and the upper wall 12 of the galley, and the prong 26 is then forced upward and outward through the 15 proper selected slot 17. This action on the spring straightens the leg portion 19, and obviously the bowed portion 20 is put under a sufficient degree of tension to insure the 20 tight or sufficiently tight grip upon the type work. The prongs or hooks 24 and 26 are somewhat differently shaped so that the prong 26 may be snapped into or out of its locking position irrespective of the material swinging movement of the spring as a whole.

25 I claim:

1. In a page galley and type tie-up, a galley having a flat bottom and certain vertical walls connected therewith, said walls having openings on the remote sides of the 30 galley, and a tie-up spring so constructed as to embrace the type matter on the otherwise open sides thereof, said spring having ends to enter and interlock in said openings in the vertical walls.

35 2. Mechanism as set forth in claim 1 in which the openings are formed in end walls of the galley in substantially diametrically opposite portions of the galley.

3. Mechanism as set forth in claim 1 in which the galley is provided with a side wall 40 in addition to the vertical walls specified which are two end walls extending from the ends of the side wall, and the openings specified are located in the end walls and in pluralities, one plurality being adjacent to the 45 side wall corner of one end wall, while the other plurality are adjacent to the open side of the galley.

4. The combination with a printer's galley having end and side walls, certain of the 50 walls being provided with vertical slots, of a locking spring for tying up the type on the galley, said spring being made from flat stock and having two arms arranged substantially at right angles to each other, one 55 of the arms being straighter than the other, and each arm terminating in a prong adapted to enter a slot in the galley for holding the spring in type tying position.

5. Mechanism as set forth in claim 4 in 60 which the spring has adjacent to each prong a shoulder to limit the extent of movement of the pronged portion through its slot.

6. Mechanism as set forth in claim 4 in which the spring is so formed that the 65 curved arm thereof is provided with a flat central portion for better abutting co-operation with the type matter on the galley.

7. Mechanism as set forth in claim 4 in which the straighter arm of the spring is 70 provided with a normally flat or obtuse angle to increase the tension against the type matter when interlocked.

In testimony whereof I affix my signature.

EDWARD SYLVESTER KELLEY.
